J. Keller.

Brick Mach.

No 90,555.

Patented May 25, 1869.

United States Patent Office.

JOHN KELLER, OF PADUCAH, KENTUCKY, ASSIGNOR TO HIMSELF, F. J. FAIRBANK, AND J. W. COLE, OF SAME PLACE.

Letters Patent No. 90,555, dated May 25, 1869.

IMPROVED BRICK-MACHINE.

The Schedule referred to in these Letters Patent and making part of the same.

To all whom it may concern:

Be it known that I, JOHN KELLER, of Paducah, in the county of McCracken, and State of Kentucky, have invented a new and useful Improvement in Brick-Machine; and I do hereby declare that the following is a full, clear, and exact description thereof, which will enable others skilled in the art to make and use the same, reference being had to the accompanying drawings, forming part of this specification, in which—

Figure 1, Sheet No. 1, represents a vertical central section of my invention.

Figure 2 is a detached external view of a part pertaining to the same.

Figure 3, Sheet No. 2, is a horizontal section of the same, taken in the line x x , fig. 1.

Figure 4 is a horizontal section of the same, taken in the line y y , fig. 1.

Figure 5 is a horizontal section of the same, taken in the line z z , fig. 1.

Similar letters of reference indicate like parts.

This invention relates to a new and improved machine for pressing and moulding brick; and has for its object, first, the pressing of the clay very compactly in its mould, so that firm, solid bricks will be obtained; and, second, the performing of the work above specified in a very expeditious manner.

The framing of the machine is composed of two parts, A B, the lower part, A, consisting of a base, a^x , having four uprights, b^x , attached to it, with circular horizontal supports C D secured to their upper parts.

The part B of the frame is a circular or polygonal box, which is fitted on the top of A.

Within the box B there is fitted a cylindrical case, E, of metal or wood, which is fixed or stationary, and is encompassed by a case, F, having a toothed rim, G, secured to the exterior of its upper part.

This case F is allowed to turn freely around the stationary case E, and it has two inclined ribs, a a' , which are inclined in opposite directions, as shown in fig. 2, and also a horizontal rib, b , which extends around the case F, from the upper end of rib a' , nearly to the upper end of the other rib, a .

The case F is rotated by toothed wheels H, on a vertical shaft, I, the wheel H gearing into the toothed rim G, the shaft I receiving its motion by gear-wheels J J', from the lower end of a vertical shaft, K, which passes centrally through the whole machine, as shown clearly in fig. 1.

On the upper part of the shaft K, which is within the case E, there are horizontal arms L, and these arms, in connection with the case E, constitute the mud-mill in which the clay is tempered, the lower

arms, L, serving as the scrapers, and forcing the tempered clay down through openings c in the bottom d of case B, and within the case E.

In this bottom d there are also made openings, one at the outer side of each opening c, and at the outer side of the case E, and through these openings plungers M work, said plungers being moved or forced down by the rib a , raised by rib a' , and retained in an elevated position by the horizontal rib b .

The plungers M are fitted and work in vertical grooves e, made in the inner side of the case B, (see fig. 3,) and screws f pass through oblong vertical slots e^x , in the case B, and through the plungers M, the inner ends of these screws being acted upon by the ribs a a' b .

The support C contains the brick-moulds h, in which horizontal plungers N work. (See more particularly fig. 4.)

These moulds are open both at top and bottom, and the plungers are operated by a cam, O, on the shaft K.

These plungers are connected, in pairs, by plates P, which have oblong slots i made through them, for the shaft K to pass through, the oblong slots admitting of a proper length of movement of the plungers.

The two plungers N of each pair are in line with each other at opposite sides of shaft K, so that when one plunger of a pair is being forced into its mould the other one is being withdrawn from its mould. This will be fully understood by referring to fig. 4.

The tops of the moulds are closed, when necessary, by means of slides Q, connected in pairs by plates R, and operated by a cam, S, on shaft K.

This arrangement is precisely like that of the plungers N, as will be seen by referring to fig. 3.

The slides Q, when drawn inward underneath a circular plate, T, which covers the plates R, that connect the slides.

The bottoms of the moulds are closed, when necessary, by slides U, (see fig. 5,) said slides being forced outward to close the bottom of the mould, by means of a cam, V, on shaft K, and drawn inward by a cam, W.

X is a circular rotating platform, which is fitted loosely on shaft K, and has a toothed rim, Y, attached to its under side, into which, and the wheel J', a pinion, Z, on a driving-shaft, A x , gears. (See fig. 1.)

Directly over this platform X, and to the under side of the support D, there is attached a bar, B x , which serves to discharge the bricks or moulded clay from the platform, as will be presently described.

The clay, as the slides Q are drawn back, passes down into the moulds h, a slide, U, being closed, or underneath each mould, as the clay is forced into it.

As each mould is filled, a slide, Q, passes over it, so

that the clay will be completely enclosed all around, and the plunger N of the closed mould then is operated, and the clay therein compressed.

The slides Q U are then drawn back with the plungers N, and a plunger, M, is forced down to discharge the compressed clay from the mould.

The slides and plungers all operate successively, one after the other, the cams on shaft K, and the ribs a' b on case F, being so placed or arranged as to effect that end.

The bricks or compressed clay drop from the moulds upon the table X, and are discharged therefrom by coming in contact with the bar B^X.

Having thus described my invention, I claim as new, and desire to secure by Letters Patent—

1. The series of plungers N, working radially to press the bricks between two series of radial slides, Q U, which open and close the tops and bottoms of the moulds, in combination with the vertical plungers M, for discharging the bricks upon the table X, all constructed and arranged substantially as described.

2. The series of moulds h, with the reciprocating plungers N and slides Q U; the rotating table X, and guide-bars B X, all constructed, arranged, and operating as and for the purposes herein set forth.

JOHN KELLER.
